ABRASIVE THROWING MACHINE

John E. Guendling, South Bend, Ind., assignor to
 The American Foundry Equipment Company,
 Mishawaka, Ind., a corporation of Delaware

Application March 22, 1938, Serial No. 197,339

11 Claims. (CL 51—9)

This invention relates to abrasive throwing machines and more particularly to a throwing wheel of the centrifugal type having improved means for controlling the direction of flight of the thrown abrasive.

According to the invention, the machine comprises a rotor having a plurality of throwing blades extending from the periphery of the rotor to points inwardly short of the axis of rotation of the wheel to provide a central space, the blades being suitably mounted for rotation about the axis of the rotor. Abrasive is fed to the rotating blades through a control member extending into the space provided centrally of the 10 rotor and having an abrasive discharge outlet in the tubular side wall thereof. An impeller comprising one or more vanes which extend into the tubular control member and is mounted to rotate with the blades to throw abrasive through 15 the discharge outlet in the control member and into the path of rotation of the blades. The control member and impeller are so shaped and positioned relative to each other and to the other portions of the rotor as to minimize the entry 20 of uncontrolled abrasive material into the path of rotation of the blades, thus reducing the possibility of clogging or undue wear.

In an illustrative embodiment of the invention the control member comprises a generally tubular side wall portion which is open at one end to permit the entry of abrasive and closed at the other end as by an end wall. A stud extends from the end wall into the tubular side wall portion but is spaced therefrom to permit the impeller to run in the space therebetween. The stud provides a means by which the control member may be adjustably supported. The stud may be tubular in form and may be connected to the discharge end of the feed pipe so that the abrasive may pass into the tubular stud and escape therefrom through one or more openings provided therein. The impeller comprises a member having a plurality of spaced, generally radial vanes positioned between the stud and the tubular side wall portion of the control member and a portion which is secured to the feed side of the rotor to securely and rigidly support the impeller with respect to the rotor blades.

An object of the invention is the provision of 50 an abrasive throwing machine provided with a device for controlling the direction of flight of the abrasive, which device is so constructed as to minimize clogging or wear of the parts.

Another object of the invention is to provide 55 an abrasive throwing wheel of the type having

rotating blades and a relatively fixed control member for controlling the supply of abrasive material to the blades wherein spillage of the abrasive is minimized and wherein any abrasive which is not deposited on the blades is removed 5 from the interior of the wheel.

Still another object of the invention is the provision of an abrasive throwing wheel of the type having rotating blades and an impeller rotatable therewith wherein the impeller is 10 firmly and securely mounted in a novel manner, for rotation with the blades.

Various other features and advantages of the invention will be apparent from the following particular description and from an inspection 15 of the accompanying drawings.

Although the novel features which are believed to be characteristic of this invention will be particularly pointed out in the claims appended hereto, the invention itself, as to its objects and 20 advantages, and the manner in which it may be carried out, may be better understood by referring to the following description taken in connection with the accompanying drawings forming 25 a part thereof, in which

Fig. 1 is a fragmentary, side elevational view of an abrasive throwing rotor constructed in accordance with the invention, having the improved device for controlling the direction of discharge of the thrown abrasive incorporated 30 therewith;

Fig. 2 is a transverse cross-sectional view taken along line 2—2 of Fig. 1;

Fig. 3 is a longitudinal cross-sectional view 35 through the machine taken along line 3—3 of Fig. 2;

Fig. 4 is a fragmentary cross-sectional view taken along line 4—4 of Fig. 2 and through the improved control device associated with the 40 abrasive throwing rotor;

Fig. 5 is an exploded perspective view of certain operative elements forming the control device, certain parts being broken away to illustrate more clearly certain features of the construction;

Fig. 6 is a fragmentary cross-sectional view of the central portion of the rotor and showing an alternative form of control member;

Fig. 7 is a fragmentary cross-sectional view 50 taken along line 7—7 of Fig. 6;

Fig. 8 is a fragmentary perspective view of the alternative form of control member shown in Fig. 6;

the central portion of the wheel and showing an alternative form of impeller;

Fig. 10 is a fragmentary cross-sectional view taken along line 10—10 of Fig. 9;

5 Fig. 11 is a fragmentary side elevational view of the discharge end of the feed pipe and the tubular control member, showing alternative means which may be employed for securing these parts together, certain parts being shown in section to 10 more clearly illustrate the construction; and

10 Fig. 12 is a cross-sectional view taken along line 12—12 of Fig. 11.

15 In the following description and in the claims, various details will be identified by specific names 20 for convenience, but they are intended to be as generic in their application as the art will permit. Like reference characters denote like parts 25 in the several figures of the drawings.

20 The improved device for obtaining more accurate directional control of the thrown particles 30 may be associated with any suitable rotor adapted to be driven at high speed and provided with suitably arranged abrasive throwing blades. Referring particularly to Figs. 1, 2 and 3, there is 35 shown for purposes of illustration one form of rotor which may be used, comprising a rotor disc or side wall member 1 which is operatively secured to a high speed drive shaft 6. To give 40 strength and sturdiness to the construction a hub member 7 is suitably splined or otherwise secured to the drive shaft 6 and is secured by bolts 8 or other means to the rotor disc 1.

35 One or more abrasive throwing blades b are 45 suitably mounted on the rotor disc 1 and extend inwardly short of the axis of rotation of the rotor whereby their inner ends define a central space a. To provide additional support for the blades b, and 50 to provide a support to which the rotating impeller, hereafter described, may be secured, a side wall member or disc 2 having a central opening 55 therein may be provided. The disc member 2 may be held in substantially parallel, fixed, spaced relationship with the rotor disc 1 by any suitable means. For purpose of illustration, there 45 is shown a series of spaced studs 3 having shoulders 4 thereon, which abut the inside face of the adjacent side wall plates 1 and 2 and heads 5, which are burnished or otherwise suitably secured to the side wall plates 1 and 2.

50 The blades b may be held in fixed, suspended 60 position between the side wall plates by providing paired radially extending grooves in the side wall plates 1 and 2 within which the side edges of the blades seat. There is shown for purposes of illustration a throwing wheel having a series of 65 eight, spaced, radially arranged blades b, each comprising a throwing surface or bottom wall portion 70 and flange or side wall portions 71 extending in the direction of rotation of the wheel 70 to confine the moving abradant or comminuted material on the working face 70 of the blade b and between the side flange 71 thereof. The blades b may be secured in place by set screws 90 75 extending through one of the side plates and entering notches or depressions 91 in the blades b.

To insure smooth pick-up of the abradant material at the inner end of the blade b, the inner end of the blade b is formed with a relatively thin 70 edge 72 which may be produced by rounding, chamfering, or otherwise shaping the rear face of the blade b at the inner end thereof, as shown at 73 in Fig. 3.

To obtain a high degree of directional control 75 of the thrown material and to insure a smooth

movement of substantially all of the abradant material onto the inner end of the blade during a predetermined limited arc of rotation thereof, a tubular control member is provided. As shown more particularly in Figs. 2, 3 and 5, the tubular control member or control sleeve 50 comprises a tubular side wall 15 which is generally cylindrical in exterior and interior outline. The inside surface of wall 15 may be slightly spiraled in cross-sectional contour, as indicated in Fig. 3, thereby aiding the feeding of abradant and preventing choking. The inner end of the tubular side wall 15 may be entirely closed by an end wall 16, shown more particularly in Figs. 2 and 5.

5 A discharge outlet is provided in the side wall 15 15. This outlet may comprise a single opening o adjacent the path of rotation of the inner ends of the throwing blades b or may be constituted by a plurality of suitably disposed openings, such as shown in Patents Nos. 2,077,635 and 2,077,636, 20 which may be so dimensioned and arranged as to provide an abrasive stream of substantially uniform distribution of abrasive, or which may impart to the stream any other desired distribution characteristic.

15 The tubular control member extends into the central space a defined by the inner ends of the blades b of the rotor with the closed end 16 positioned adjacent the rear rotor disc 1. Preferably, the free edge 17 of the tubular side wall 15 30 of the blades and, as shown in Fig. 2, may conveniently extend beyond the outside face of the side wall plate 2. The tubular control member does not rotate with the rotor but remains in a substantially fixed or controlled position during operation.

35 The clearance between the inner ends of the blades b and the side wall 15 of the tubular control member should be small, and preferably, 40 only such clearance is provided as is necessary to insure safe operation of the rapidly rotating rotor with respect to the stationary control sleeve.

45 The control sleeve may be mounted in fixed normally stationary position by any suitable means. Referring now to Figs. 2 and 5, such mounting means may comprise a hollow stud 18 which projects inwardly and is secured to the end wall 16 of the control sleeve, sufficient space 50 being provided between the hollow stud 18 and the inside contour of the tubular side wall 15 of the control sleeve to permit satisfactory rotation and operation of impeller vanes (hereinafter described) of suitable size therebetween.

55 The abrasive is fed into the hollow stud 18 and escapes through one or more discharge openings 19' therein, the openings 19' being defined by suitable legs or straps 19 forming a part of the control sleeve supporting stud. The supporting stud 18 may be suitably secured to the end of and supported by a supply pipe 20 of such length and of such diameter as to supply the required amount of the abradant material to be thrown from the wheel.

60 A suitable supply hopper or funnel 21, which may be secured to the upper end of the feed pipe 20, is so shaped as to assist the movement of the material into the feed pipe 20. In the event the tubular control sleeve is mounted on 70 the end of the supply pipe 20, it is necessary that the supply pipe 20 be securely mounted in fixed position, so that no movement of the tubular control sleeve during operation of the wheel will occur.

There is illustrated in Figs. 1 and 2 one form of supply pipe and control sleeve support which may be used. A foot plate 22, which may integrally be secured to the feed pipe 20 by a supporting web 23, is arranged to rest on a supporting bracket 30. The supporting bracket 30 may be provided with a flange 29 secured as by a pair of spaced bolts 28 to an upwardly extending flange 27 on another bracket 30', having a foot portion 25 which rests upon a fixed frame member or abutment 24 and is secured thereto as by a bolt or bolts 26.

The downwardly extending flange portion 29 of the supporting bracket 30 may be provided with a slot 29' to receive the bolts 28 and which permits shifting of the feed pipe 20 and the control sleeve mounted thereon axially with respect to the central space *a* of the rotor. Likewise, the foot portion 22 associated with the feed pipe 20 may also be provided with a slot 32 through which the bolt 31 extends to permit lateral shifting of the feed pipe 20 and the control sleeve mounted on the end thereof to properly center the control sleeve within the central space *a* of the rotor. The flange portion 27 of the second bracket 30' may also be provided with vertically extending slots through which the bolts 28 extend to permit vertical adjustment of the feed pipe 20 and the control sleeve attached to the inner end thereof. Thus, three adjustments are provided to permit proper positioning and centering of the control sleeve within the central space *a* of the rotor.

The supply pipe 20 and the control sleeve may be held in fixed position by proper adjustment and tightening of the bolts 28 and 31. It is appreciated that numerous different types of adjustable supports may be provided for supporting the feed pipe 20 and the control sleeve associated therewith.

To lessen the weight imposed upon the supporting bracket 20, the supply funnel or hopper 21 may be independently supported by an arm 33 extending upwardly from the foot portion 25, which arm is secured to a bracket 34 as by bolts 34', the bracket 34 being suitably attached to the supply funnel or hopper 21.

A leakproof seal between the inner end of the supply pipe 20 and the hollow supporting stud 18 extending inwardly from the control sleeve, may be provided in numerous ways. Such leakproof seal may be formed by providing a hollow fitting 36 extending outwardly from the hollow stud 18, which fitting telescopes into and has a machined fit with a hollow boss 35 on the inner end of the supply pipe 20. The fitting 36 is so constructed that the inside face thereof is substantially continuous with the inside surface of the supply pipe 20 so that no abrupt or irregular projections occur which might impede the normal smooth flow of the abrading material.

To further insure the sealtight fit between these parts, a shoulder 37 may be provided on the interior of the feed pipe 20 against which abuts the free end 38 of the fitting 36. Similarly, a shoulder 39 is provided on the hollow stud 18 against which abuts the free end 40 of the feed pipe 20. The control sleeve may be locked to the inner end of the feed pipe 20 by a spring collar or clip 43 provided with inwardly projecting studs 44. The hollow boss 35 provided on the inner end of the feed pipe 20 is provided with corresponding openings or apertures 41 through which the studs 44 may extend.

Corresponding apertures or openings 42 may be provided with the fitting 36 forming a part of the hollow stud 18 on the control sleeve. The studs 44 are of sufficient length to extend through the apertures 41, the boss 35 and into the apertures 42 of the fitting 36.

To permit the desired orientation of the discharge outlet *o* in the tubular control sleeve, a plurality of spaced apertures 42 may be provided in the fitting 36 so as to permit any desired rotative adjustment of the control sleeve with respect to the feed pipe 20. Thus, the discharge outlet *o* in the control sleeve may be arranged in any clock dial position relatively to the axis of the rotor so that the abradant will discharge into the wheel 15 over any selected arc.

The control sleeve may be set in any desired position of adjustment by withdrawing the studs 44 from the apertures in which they are seated, rotating the control sleeve the desired amount so as to permit the studs 44 and the clip 43 to snap into the selected apertures 42 in the fitting 36 of the hollow stud associated with the control sleeve.

An impeller is provided to forcibly project the abradant out through the discharge outlet *o* in the control sleeve and in substantially the same direction as the direction of rotation of the blades *b* and at a velocity only slightly less than the angular speed of rotation of the inner ends of the blades. As shown more particularly in Figs. 2, 3 and 5, the impeller 60 comprises a pair of spaced rings or side wall plates 51 and 52 between which are arranged a series of spaced abrasive throwing vanes 53. Preferably, there is a vane 53 for each of the abrasive throwing blades *b* which are arranged so that each vane is positioned slightly in advance of the corresponding blade in the direction of rotation, as illustrated in Fig. 3. The vanes 53 are mounted for rotation within the control sleeve in the space between the side wall 15 and the hollow stud 18, whereby abrasive which is forced through the openings 19' is deposited in a path of the vanes 53 and thrown out through the discharge opening *o* of the control sleeve.

The vanes 53 and connected side plates 51 and 52 are securely mounted for rotation with the throwing blades *b*. A sleeve portion 59 extends out through the opening 2' in the side plate 2 and is attached to or preferably integral with a rim portion 58 having a mounting ring or flange 55. The flange 55 is attached to the outer wall of the side plate 2 as by bolts or screws 57 extending through openings 56 in the flange 55. The flange 55 may be set back slightly so that the rim 58 is set out from the face of the side plate 2 and accommodates the open end of the side wall 15 of the control sleeve.

The sleeve portion 59 of the impeller is spaced from the edge of the opening 2' in the side plate 2 to provide a space to accommodate the side wall 15 of the control member 50, this space, however, being preferably only sufficiently large to permit the proper clearance, thus preventing the accumulation of abradant material therein. The sleeve portion 59 is provided with a shoulder 54 to accommodate the correspondingly shaped portion 15' of the control sleeve 50.

In order to permit the escape or spillage of any abradant which enters the space *a* defined by the inner ends of the blades *b* and which is not deposited in the path of the blades *b*, one or more spillage openings 61 are provided. In the present embodiment the spillage openings 61 are formed in the rim portion 58 of the impeller and take the

form of elongated slots. Thus, if any abradant collects in the space a and is not deposited in the path of the blades b , it will be ejected through the spillage openings 60 . The movement of the vanes 53 and the blades b will agitate any abradant material sufficiently so that it will either be picked up by the vanes 53 and thrown into the path of the blades b or will be carried to the openings 61 and expelled therethrough.

The construction of the control member 50 and particularly the provision of the completely closed end wall 16 , minimizes or completely prevents the leaking of abradant from the space within the side wall 15 and thus substantially all the abrasive is positively directed and is hurled through the opening o and into the path of the blades b . Since the free, open end of the side wall 15 extends past the edges of the blades and through the side wall 2 , the abrasive in the sleeve is positively directed out of the wheel and there is little possibility of "leakage" of abrasive into the space between the control sleeve and the blades and side plates.

The wheel may be assembled in a manner which will be apparent to those skilled in the art from an inspection of the drawings and a reading of the foregoing description. However, it should be noted that, if desired, the control sleeve, feed supply pipe and the impeller 60 can be first assembled together, and these members thereafter assembled with the remainder of the wheel. In an analogous manner, whenever repairs or adjustments are to be made, the feed pipe, control member and impeller can be removed from the wheel as a unit.

In the operation of the wheel, the shaft 6 is rotated thereby rotating the hub member 7 , side plates 1 and 2 and throwing blades b as a unit. The impeller 60 carried by the side plate 2 also rotates with the throwing blades. The control member 50 , being relatively fixed, does not rotate and the opening o or openings remain in a fixed clock dial position. Commminuted material, such as abradant material, is delivered to the hopper 21 and flows or is suitably forced through the supply pipe 20 and through the fitting 36 and is delivered into the interior of the hollow stud 18 from which it flows through one or more of the openings 19 and into the path of movement of the vanes 53 . The rotating vanes 53 carry the abradant material with them and throw it out through the opening o and into the path of the blades b . The material is picked up by the blades b and carried to the periphery of the wheel where it is hurled from the blades at the desired velocity. The other factors being equal, the direction of flight of the abrasive as it leaves the wheel is determined by the clock dial position of the opening o , which position can be adjusted by adjusting the position of the control member 50 in the manner previously described.

Certain modifications can be made in the structure hereinbefore described without departing from the spirit of the invention. Referring now particularly to Figs. 6, 7 and 8, there is shown an embodiment of the invention wherein an alternative construction of control member is employed, the remaining portions of the wheel being similar in all respects to the corresponding parts illustrated in Figs. 1 to 5.

The wheel comprises a plurality of throwing blades 170 carried by said plates 101 and 102 and suitably mounted on shaft 106 for rotation, as above described. The impeller 160 is carried on the side plate 102 and has throwing vanes 153

disposed in the space a' defined by the inner ends of the blades 170 , as described hereinbefore.

The feed pipe 120 leads to the space a' and communicates with and supports a control member 150 of modified construction. The control member 150 comprises a tubular side wall 115 having an opening o or a plurality of openings, as disclosed in the patents above referred to. The tubular side wall member 115 is closed at its side opposite the feed end of the wheel by an end wall 116 . The control member is mounted in position in the central space a' by a stud 119 extending from the end wall in the space enclosed by the side wall 115 . The stud 119 preferably is arcuate in form in order to provide increased rigidity and preferably extends over approximately a 90° arc. The stud is positioned so that it does not interfere with the passage of abrasive from the feed pipe 120 to the path of the vanes 153 and is suitably secured to the end of the feed tube 120 , a fitting 136 preferably of cylindrical form being provided for this purpose. The fitting 136 preferably is formed integral with the stud 119 and is machined on its outer surface to provide a seal tight fit with a hollow boss 135 formed on the end of the feed tube 120 . A shoulder 137 is provided on the feed pipe against which the free end 140 of the fitting 136 abuts. Similarly, a shoulder 138 is provided on the stud 119 against which the free end 140 of the feed pipe abuts.

A spring collar or clip 143 is provided having inwardly extending studs 144 which project through openings 141 of the feed pipe 120 and enter recesses 142 in the fitting 136 .

Referring now to Figs. 11 and 12 there is shown an alternative form of means for securing the control member to the feed pipe. In this embodiment of the invention the control member can be adjusted to any one of an infinite number of positions angularly about the axis of the wheel. The control member 250 is formed in a manner generally similar to the control member 50 but, instead of being locked to the supply pipe by a positively positioned means, is secured frictionally, whereby very close adjustments can be obtained.

In this construction the supply pipe 220 is provided with an enlarged end or boss 235 into which is telescoped a fitting or cylindrical extension 236 of the control sleeve 250 . The free end of the fitting 236 abuts a shoulder 237 on the supply pipe 220 and the interior surfaces of the supply pipe 220 and the fitting 236 extend substantially continuously to provide a smooth surface with no shoulders against which abrasive could lodge.

The boss 235 is formed as a split ring whereby it can be slightly contracted to frictionally grip the fitting 236 . Lugs 280 are formed adjacent the ends of the split boss 235 and are provided with registering openings 281 through which a bolt 282 is extended and secured as by a nut 283 . When the boss 235 is contracted slightly by tightening the nut and bolt it tightly grips the fitting 236 . It will be understood that there is a close machine-fit between the fitting 236 and the boss 235 so that a very minute contraction of the boss 235 provides a tight grip.

Referring now to Figs. 9 and 10, there is shown a construction embodying an alternative form of impeller. The remaining portions of the machine are preferably similar to the corresponding portions of the machine illustrated in Figs. 1 to 5 and described in the corresponding descriptive matter.

In the construction illustrated in Figs. 9 and 10, the impeller comprises a plurality of vanes 353 carried between side wall members 351 and 352. The vanes and side wall members are supported by a sleeve portion 359 which extends out through the opening 302 in the side wall plate 302. The sleeve portion 359 is integral with and carried by a mounting flange 355 extending substantially perpendicularly to the sleeve portion 359. The mounting flange 355 is of substantial thickness and one or more spillage ducts or openings 361 extend therethrough. Preferably, the ducts 361 extend substantially in the plane of the flange 355 in a direction from the inside to the outside. In the illustrative embodiment, four such ducts 361 are shown and each extends in a direction backwardly with respect to the rotation of the wheel.

In the operation of this form of machine, any abradant material which is deposited within the side wall 315 of the control member 350 and which is not thrown into the path of movement of the throwing blades 370, is discharged through the spillage ducts 361. The movement of the vanes 353 and the blades 370 tends to agitate such material and assist its movement toward the ducts. After the material enters the ducts it is caused to flow therethrough by the centrifugal force created by the rotation of the impeller and is forcibly ejected from the outer ends of the ducts.

It will be understood that either form of control member, either form of means for securing the control member to the supply pipe or either form of impeller may be employed with either of the forms of the remaining members of the wheel. In other words, where alternative constructions are shown, either alternative can be employed in a wheel constructed in accordance with the invention.

From the foregoing it will be seen that the present invention provides an improved abrasive throwing machine wherein uncontrolled leakage or spillage of abrasive material from the control member into the path of rotation of the blades is minimized or substantially prevented. The abrasive material is positively and efficiently delivered to the vanes of the impeller and the possibility of undue wear or clogging of the wheel is reduced to a minimum. The construction provides a simple and efficient manner of mounting the impeller by which the impeller can be securely and positively fixed relative to the throwing blades and prevented from turning or becoming displaced in such a way as to change the predetermined clearance between the rotating and stationary parts of the wheel.

The present invention provides a structure in which the supply pipe, impeller and control member occupy a minimum of the space within the inner ends of the throwing blades and interfere to the minimum extent with the smooth and full flow of abrasive material from the hopper to the throwing blades. Furthermore, the novel construction of supply pipe and control member permits a smooth unimpeded flow of abrasive material without any liability of clogging or choking.

While certain novel features of the invention have been disclosed herein, and are pointed out in the annexed claims, it will be understood that various omissions, substitutions and changes may be made by those skilled in the art without departing from the spirit of the invention.

It is to be understood that the term "abrasive," "abradant" or like terms, as herein used are intended to signify material which either is inherently abrasive, or capable of exerting an abrad-

ing action or capable of hardening or polishing the articles treated. Such material may consist of smooth particles, such as steel shot, or sharp abrasive particles, such as cracked steel grits or clean sharp quartz sand or other materials suitable for cleaning, hardening, polishing or otherwise modifying the surface characteristics of the articles in the desired manner.

What is claimed is:

1. A machine for throwing abrasive comprising a rotor including spaced parallel side members having throwing blades between said side members extending from the periphery of said rotor inwardly short of the axis of rotation thereof to provide a central space, means for feeding abrasive through one of said side members to said space, an impeller carried by a side member at the feed side of said rotor and having vanes in said central space, and a control member having a tubular portion in said space between said vanes and said blades and formed with an inlet opening at the feed side of said rotor and a discharge opening adjacent the path of rotation of the inner ends of said blades.

2. A machine for throwing abrasive comprising a rotor including spaced, parallel, side members having throwing blades carried between said side members and extending from the periphery of said rotor inwardly short of the axis of rotation thereof to provide a central space, an impeller supported from one of said side members and having vanes in said central space, a spillage opening for abrasive leading from said space through said impeller, a relatively stationary control member having a tubular portion in said space between said vanes and said blades, said tubular portion having a discharge opening therein adjacent the path of rotation of said blades, and means for feeding abrasive to said rotor through the side member on which said impeller is mounted.

3. A machine for throwing abrasive comprising in combination, a rotor including a plurality of throwing blades extending from the periphery inwardly short of the axis of rotation of the rotor to provide a central space, a relatively stationary control member having a tubular portion disposed in said central space, an impeller having a plurality of vanes rotatable with said throwing blades extending into said tubular portion, a discharge opening in the wall of said tubular portion, and means extending through said impeller for mounting said control member in normally stationary position.

4. A machine for throwing abrasive comprising in combination, a rotor including a plurality of rotatably mounted throwing blades extending from the periphery inwardly short of the axis of rotation of said rotor to provide a central space, means for feeding abrasive into said central space from one side of said rotor, a control member having a tubular portion in said central space, an impeller having a plurality of vanes in said tubular portion, and means secured to the feed side of said rotor for supporting said impeller for rotation with said blades.

5. A machine for throwing abrasive comprising in combination, a rotor including a plurality of rotatably mounted throwing blades extending from the periphery inwardly short of the axis of rotation of said rotor to provide a central space, means for feeding abrasive into said central space from one side of said rotor, an impeller having a plurality of vanes in said central space, means

secured to said rotor at the feed side thereof for supporting said impeller for rotation with said blades, a relatively fixed control member having a tubular portion extending into said central space between said vanes and said blades, and means extending through said impeller for supporting said tubular portion.

6. A machine for throwing abrasive comprising a rotor including a plurality of blades extending from the periphery inwardly short of the axis of rotation of the rotor to provide a central space, an impeller rotatable with said blades extending into said space, a control member having a tubular portion in said space between said impeller and said blades and having a mounting portion extending within said impeller, a feed member for feeding abrasive to said impeller, and means adjustably supporting the mounting portion on said feed member.

7. A machine for throwing abrasive comprising a rotor including a plurality of blades extending from the periphery inwardly short of the axis of rotation of the rotor to provide a central space, an impeller rotatable with said blades extending into said space, a control member having a tubular control portion formed with a discharge opening, said tubular control portion being disposed in said space between said impeller and said blades, and a tubular feed portion within said impeller, and a tubular feed member communicating with said tubular feed portion and having substantial continuity of internal surface therewith, whereby abrasive material is delivered through said feed member to the feed portion of said control member without spillage.

8. A machine for throwing abrasive comprising a rotor including a plurality of blades extending from the periphery inwardly short of the axis of rotation of the rotor to provide a central space, an impeller rotatable with said blades extending into said space, a control member having a tubular portion in said space between said impeller and said blades, and a tubular feed portion extending through said impeller, and a tubular feed member telescoping with said feed portion whereby said feed member and said feed portion provide a closed tube leading from outside said wheel to within said central space.

9. A machine for throwing abrasive comprising 50. a rotor including a plurality of blades extending

from the periphery inwardly short of the axis of rotation of the rotor to provide a central space, an impeller rotatable with said blades extending into said space, a control member having a tubular portion in said space between said impeller and said blades, and a support for said control member extending through a central opening in said impeller, a tubular feed spout, and means for adjustably mounting said support on said feed spout.

10. An abrasive projecting machine comprising a rotor having a plurality of rotatably mounted throwing blades extending from the periphery inwardly short of the axis of rotation of the rotor to provide a central space, means for feeding abrasive into said central space from one side of said rotor, an impeller fixed to rotate with said blades extending into said space, a control member having a tubular portion extending into said space between said impeller and said blades, said control member having a discharge outlet in the tubular portion thereof for directing the abrasive into the path of rotation of said blades, said impeller including a plurality of vanes rotatable in said tubular portion and a mounting portion fixed to said vanes, extending over the edge of said tubular portion, at the feed side of said rotor and fixed to said rotor, said mounting portion having an abrasive spillage opening therein through which stray abrasive may escape.

11. An abrasive projecting machine comprising a rotor having a plurality of rotatably mounted throwing blades extending from the periphery inwardly short of the axis of rotation of the rotor to provide a central space, means for feeding abrasive to said rotor at one side thereof, an impeller fixed to rotate with said blades extending into said space, a control member having a tubular portion extending into said space between said impeller and said blades, said control member having a discharge outlet in the tubular portion thereof for directing the abrasive into the path of rotation of said blades, said impeller including a plurality of vanes rotatable in said tubular portion and a mounting portion fixed to said vanes, extending over the edge of said tubular portion adjacent the feed side of said rotor, and fixed to said rotor.
